UNITED STATES PATENT OFFICE.

WILLIAM J. CARPENTER, OF CHICAGO, ILLINOIS, ASSIGNOR OF ONE-HALF TO JOHN J. JORDAN, OF CHICAGO, ILLINOIS.

WRENCH.

1,386,596.

Specification of Letters Patent. Patented Aug. 9, 1921.

Application filed April 28, 1919. Serial No. 293,229.

To all whom it may concern:

Be it known that I, WILLIAM J. CARPENTER, a citizen of the United States, and a resident of the city of Chicago, county of 5 Cook, and State of Illinois, have invented certain new and useful Improvements in Wrenches, of which the following is a specification.

My invention relates to new and useful 10 improvements in wrenches and has for its object the provision of a wrench which will be easily and quickly adjusted to fit various sized nuts.

Another object is the provision of a device 15 of the class described, which will automatically adjust itself to fit various sized objects with which used, and to provide automatic means of retaining said wrench in said adjusted position.

20 Other objects will appear hereinafter.

The invention consists in combinations and arrangements of parts hereinafter described and claimed.

Invention will be best understood by reference to the accompanying drawings forming a part of this specification and in which—

Figure 1 is a front elevation of a wrench embodying the device applied to an object with which used,

30 Fig. 2 represents a side elevation of a wrench embodying the invention with parts removed.

Fig. 3 is a section taken on substantially the line 3—3 of Fig. 2.

35 Fig. 4 is a detailed side elevational view of a wrench embodying the invention with parts removed.

Fig. 5 is a vertical section taken on the line 5—5 of Fig. 4. Fig. 6 is a side elevation of a wrench embodying the invention in a modified form. Fig. 7 is a rear view 40 of the wrench showing the slot and a pin passing therethrough. The preferred form of construction, as illustrated in the drawings, comprises an elongated stem or shank 6, having a stationary jaw 7. Embracing the upper end of the member 6 and pivotally fastened thereto by rivet 9, or other suitable fastening means is a sleeve housing

45 8. Cooperating with the member 7 is a movable jaw 10 having a shank 10' which is slidably mounted in the housing 8. The shank 10' is provided on one side with teeth 12, which are perpendicular to the

shank. On the opposite side of said shank 55 are teeth 11 which are inclined toward the jaw 10, the teeth 11 serving as ratchet teeth as will be explained hereinafter. As shown, the housing 8 is partially circular on one side and mounted within the circular portion of the housing 8 is a flanged disk 13 provided with teeth on the periphery thereof, the same thereby forming a gear wheel or pinion, said member 13 being rotatively mounted within said housing upon a shaft 60 14 as clearly shown in Fig. 5. This shaft 14, or the portion of the pin 14 which serves as a shaft, is seated in hub 14', which projects inwardly from disk 15 which is fixedly mounted within said housing, adjacent one 65 of the sides thereof, by means of a square pin 15' inserted in the wall of said housing, or any other suitable means of fastening. Mounted within this housing and secured to the inner side of the flanged portion of 70 the member 13, at one end 17 is a helical spring 16, the other end 18 of which is securely fastened to the inwardly projecting hub 14', as clearly seen in Fig. 4.

A shaft 19 projects through the housing 8 and mounted within said housing fixedly to said shaft is a dog on pallet 21, adapted to engage with the teeth 11 on shank 10'. Fixedly mounted on the shaft 19, outside of the housing 8, is a member 20, which serves 85 as a means for releasing the member 21 from engagement with the teeth on shank 10'. These members 20 and 21 being fixedly mounted on the same shaft 19, it is evident that upon the rocking of the member 20 in 90 a direction toward shank 10', that the member 21 will thereby be disengaged from the teeth of said shank. In order to lock the movable jaw relatively to the stationary jaw so that the relative distance between 95 these two jaws will remain the same while the wrench is being operated to turn a nut or pipe, the dog 20 is moved in a direction away from the shank 10', thereby forcing the dog 21 into engagement with the teeth 11. 100

Mounted upon the member 6 at the upper end thereof, by means of the screw 24 is a plate spring 23, which is the ordinary plate spring positioned on pipe wrenches of this type.

105 As is evident from the description and drawings, a device is provided in which the movable jaw may be moved away from the

fixed jaw, upon the release of the dog 21 from the shank 10', and the appliance of pressure upwardly against the lower end of said shank. As this movable jaw moves 5 away from the fixed or stationary jaw, the teeth which are perpendicular to the shank 10' being in constant mesh with the teeth provided on the member 13, will cause the said member 13 to rotate, and will thereby 10 wind the helical spring fastened thereto, and consequently increase the tension of the said spring. The spring will then have a tendency to restore the member 13 to its original 15 position, and thus will cause the shank 10' to move to normal position, thereby causing the movable jaw to approach the stationary jaw.

The teeth 11 being ratchet teeth will slide over the dog 21, the end of the said dog engaging in its turn with each succeeding tooth as it passes. With a device of this kind, in applying the same to the object which is to be operated upon (such as for instance a pipe or a nut), all that is necessary 20 is to push the movable jaw away from the stationary jaw, and engage the object between the two jaws. The member 13 responding to the tension of the helical spring 16 will then draw the movable jaw 25 toward the fixed jaw, until the object to be operated upon is engaged by both the fixed and the stationary jaws. To release the wrench from the object which is operated upon, the member 20 is pushed inwardly 30 as already described, which will allow the movable jaw to be free for movement away from the stationary jaw. In Fig. 6 I have shown a modified form of my construction in which the means for holding the movable 35 jaw 10 in fixed relation to the stationary jaw 7 comprises a dog 21' fixedly mounted within the housing 8, upon the shaft 19. Fixedly mounted to the shaft 19 within the housing 8, and projecting laterally from 40 the said shaft 19 is an arm or bell crank 28, one end of which is pivotally connected to a bar 25, which is provided with a longitudinal slot 28 and which has its lower end angularly turned to form the projection 45 27. Projecting through the slot, which is provided in the member 25, is a bolt 26 which is fastened to the member 6, thereby affording slidable movement of the bar 25 relatively to the bolt 26, as will be readily 50 understood. From this arrangement it is seen that by pressing the end 27 toward the stationary jaw 7, that the dog 21' is released 55 from the teeth 11 thereby allowing the movable jaw 10 to be moved away from the stationary jaw 7.

The utility of such a device is readily apparent, inasmuch as a wrench is provided which may be adjusted to fit any size nut or pipe within its range almost instantly, such 60 65 a device thereby resulting in a great saving

of time. The structure of the device is such as to be durable and efficient in use and economical of manufacture.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A wrench comprising a shank having a stationary jaw on the upper end thereof; a movable jaw having a projecting shank provided with teeth on opposite sides, the teeth on one side being perpendicular to the said shank and the teeth on the opposite side being angularly inclined thereto; a sleeve housing embracing said shanks, and mounted adjacent its upper edge on said stationary jaw; a pinion rotatively mounted in said housing and adapted to mesh with said perpendicular teeth; and resilient means co-operating with said pinion to move said movable jaw toward said stationary jaw when said movable jaw is moved therefrom; and means for locking said jaws in position; substantially as described.

2. A wrench comprising a shank having a stationary jaw on the upper end thereof; a movable jaw having a projecting shank provided with teeth on opposite sides, the teeth on one side being perpendicular to the said shank, and the teeth on the opposite side being angularly inclined toward said movable jaw; a sleeve housing embracing said shanks and mounted on said stationary jaw; a pinion rotatively mounted in said housing and adapted to mesh with said perpendicular teeth; resilient means co-operating with said pinion to move said movable jaw toward said stationary jaw when said movable jaw is moved therefrom; and means for locking said jaws in position; substantially as described.

3. A wrench comprising a shank having a stationary jaw at the upper end thereof; a movable jaw having a projecting shank, having teeth on opposite sides, the teeth on one side being perpendicular to said shank, and the teeth on the opposite side being angularly inclined to and toward said movable jaw; a sleeve housing embracing said shanks, and secured adjacent to its upper edge, to the lower portion of said stationary jaw; a pinion mounted in said housing and adapted to mesh with said perpendicular teeth; resilient means co-operating with said pinion to move said movable jaw toward said stationary jaw when said movable jaw is moved therefrom.

is moved therefrom; means coöperating with said inclined teeth to prevent said movable jaw from being moved away from said stationary jaw, substantially as described.

5 4. A wrench comprising a shank having a stationary jaw at the upper end thereof; a movable jaw having a projecting shank, having teeth on opposite sides, the teeth on one side being perpendicular to said shank, and the teeth on the opposite side being angularly inclined to said shank and toward said movable jaw; a sleeve housing embracing said shanks and secured adjacent to its upper edge to the lower portion of said stationary jaw; a pinion mounted in said housing and adapted to mesh with said perpendicular teeth; a helical spring secured to said pinion and adapted, when said pinion is rotated, to restore the same to its original 70 position, a dog mounted in said housing and engaging with said inclined teeth to prevent said movable jaw from being moved away from said stationary jaw; and a means for releasing said dog from engagement with 75 said teeth, substantially as described.

10 15 5. A wrench comprising a shank having a stationary jaw at the upper end thereof; a movable jaw having a projecting shank having teeth on opposite sides, the teeth on one side being perpendicular to said shank, and the teeth on the opposite side being angularly inclined toward said movable jaw; a sleeve housing embracing said shanks, and mounted adjacent to its upper edge to the 80 lower portion of said stationary jaw; a pinion mounted in said housing and adapted to mesh with said perpendicular teeth; resilient means coöperating with said pinion to move said movable jaw toward said stationary jaw when said movable jaw is moved therefrom; and means 85 mounted in said housing coöperating with said inclined teeth to prevent said movable jaw from being moved away from said stationary jaw, substantially as described.

25 30 35 40 6. A wrench comprising a shank having a stationary jaw at the upper end thereof; a movable jaw having a projecting shank having teeth on opposite sides, the teeth on one side being perpendicular to, and the teeth on the opposite side being angularly inclined to, said shank; a sleeve housing embracing said shank and secured adjacent to its upper edge, to the lower portion of said stationary jaw; a pinion mounted in said housing and adapted to mesh with said perpendicular teeth; a helical spring secured to said pinion and adapted, when said pinion is rotated, to restore the same to its original 90 position; and means for locking said jaws in position; substantially as described.

45 50 55 60 7. A wrench comprising a shank having a stationary jaw at the upper end thereof; a movable jaw having a projecting shank having teeth on one side being perpendicular to said shank, and the teeth on the opposite side of said shank being angularly inclined toward said movable jaw; a sleeve housing embracing said shank and being pivotally secured adjacent to its upper edge to the lower portion of said stationary jaw; a pinion mounted in said housing and adapted to mesh with said perpendicular teeth; a helical spring secured to said pinion and adapted, when said pinion is rotated, to restore the same to its original position, and a dog mounted in said housing and engaging with said inclined teeth to prevent said movable jaw being moved away from said stationary jaw, substantially as described.

65 8. A wrench comprising a shank having a stationary jaw at the upper end thereof; a movable jaw having a projecting shank having teeth on opposite sides, the teeth on one side being perpendicular to said shank,

and the teeth on the opposite side of said shank being angularly inclined toward said movable jaw; a sleeve housing embracing said shank and pivotally mounted adjacent to its upper edge to the lower portion of said stationary jaw; a pinion mounted in said housing and adapted to mesh with said perpendicular teeth; a helical spring secured to said pinion and adapted, when said pinion is rotated, to restore the same to its original 70 position, a dog mounted in said housing and engaging with said inclined teeth to prevent said movable jaw from being moved away from said stationary jaw; and a means for releasing said dog from engagement with 75 said teeth, substantially as described.

8. A wrench comprising a shank having a stationary jaw at the upper end thereof; a movable jaw having a projecting shank having teeth on opposite sides, the teeth on one side being perpendicular to said shank, and the teeth on the opposite side being angularly inclined toward said movable jaw; a sleeve housing embracing said shanks, and mounted adjacent to its upper edge to the 80 lower portion of said stationary jaw; a pinion mounted in said housing and adapted to mesh with said perpendicular teeth; resilient means coöperating with said pinion to move said movable jaw toward said stationary jaw, when said movable jaw is moved therefrom, and a dog fixedly mounted on a shaft in said housing engaging with said inclined teeth to prevent said movable 95 jaw from being moved away from said stationary jaw, substantially as described.

9. A wrench comprising a shank having a stationary jaw at the upper end thereof; a movable jaw having a projecting shank having teeth on opposite sides, the teeth on one side being perpendicular to said shank, and the teeth on the opposite side being angularly inclined to said shank and toward said movable jaw; a sleeve housing embracing said shanks, and mounted adjacent to its upper edge to the lower portion of said stationary jaw; a pinion mounted in said housing and adapted to mesh with said perpendicular teeth; means coöperating with said pinion to move said movable jaw toward said stationary jaw, when said movable jaw is moved therefrom; and a dog fixedly mounted on a shaft in said housing engaging with said inclined teeth to prevent said movable 105 jaw from being moved away from said stationary jaw, substantially as described.

10. In testimony whereof I have signed my name to this specification in the presence of 110 two subscribing witnesses.

WILLIAM J. CARPENTER.
